George M. Norton's Design for a Glove Plate
No 72

Patented July 25, 1846

Figure 1.

From W. P. Elliott's Patent Agency
Washington City, D.C.

UNITED STATES PATENT OFFICE.

GEORGE M. NORTON, OF ROCHESTER, NEW YORK.

DESIGN FOR A STOVE.

Specification forming part of Design No. 72, dated July 25, 1846.

To all whom it may concern:

Be it known that I, GEORGE M. NORTON, of Rochester, in the county of Monroe and State of New York, have invented a new Design for a Stove-Plate, which is described as follows, reference being had to the annexed drawing of the same, making part of this specification.

The figure is a perspective view of the ornamented stove plate.

What I claim as my invention, and desire to secure by Letters Patent, is—

A design for a new and ornamented stove-plate, as herein described and represented.

GEO. M. NORTON.
